(57) **CLAIM**

The ornamental design for a pedalboard, as shown and described.

DESCRIPTION

FIG. 1 is a perspective view of a pedalboard showing our new design;

FIG. 2 is a top view thereof;

FIG. 3 is an enlarged view of the indicated portion in FIG. 1;

FIG. 4 is an enlarged view of the indicated portion in FIG. 2; and,

FIG. 5 is a top view thereof, showing the state while in use. The evenly spaced dashed broken lines illustrate portions of the article that form no part of the claimed design. The dot-dash broken lines represent the boundaries of the claimed design, and form no part thereof. The dot-dot-dash broken lines depict the limits of the enlarged views and form no part of the claimed design.
